(57) **CLAIM**

The ornamental design for a bracket for securing concrete finishing tools, as shown and described.

DESCRIPTION

FIG. 1 is a top front left perspective view of a bracket for securing concrete finishing tools showing my new design; FIG. 2 is a bottom front right perspective view thereof; FIG. 3 is a front view thereof, the rear view being a mirror image of the front view; FIG. 4 is a right side view thereof, the left side view being a mirror image of the right side view; FIG. 5 is a top view thereof; FIG. 6 is a bottom view thereof; and, FIG. 7 is a bottom front left environmental view thereof. Portions shown in broken line are for illustrative purposes only and form no part of the claimed design. The broken lines shown in the Figures show environment and form no part of the claimed design.

1 Claim, 3 Drawing Sheets
